DESIGN FOR AN INKWELL BASE SUPPORT

Albert S. Brand, Boston, Mass., assignor to The Carter's Ink Company, Cambridge, Mass., a corporation of Massachusetts

Application July 12, 1940, Serial No. 93,586

Term of patent 3½ years

To all whom it may concern:

Be it known that I, Albert S. Brand, a citizen of the United States and resident of Boston, in the county of Suffolk, State of Massachusetts, have invented a new, original, and ornamental Design for an Inkwell Base Support, of which the following is a specification, reference being had to the accompanying drawing, forming part thereof.

Fig. 1 is a perspective plan view for an inkwell base support, showing my new design.

Fig. 2 is a front elevation thereof; and

Fig. 3 is a side elevation thereof.

I claim:

The ornamental design for an inkwell base support, as shown.

ALBERT S. BRAND.
